UNITED STATES PATENT OFFICE.

CLARENCE SCHULDT, OF DES PLAINES, ILLINOIS.

THREE-WAY LAMP SOCKET.

Application filed July 22, 1925. Serial No. 45,340.

This invention relates to lamp sockets having a three way circuit.

An object of the invention resides in providing a lamp socket having a three way or three wire circuit leading thereto for conveying the source of power to the socket, and which is provided with a switch mechanism for controlling the wire connections with the socket so as to control a lamp 10 mounted in the socket independently of a remote controlling switch with which the three wire circuit connects in order that the lamp may be either controlled from a wall switch or the switch thereon.

15 A further object of the invention resides in providing a combined lamp socket and switch construction for a three wire circuit wherein the switch construction in the lamp socket is adapted to control the circuit to 20 the socket independently of the remote control switch, and wherein the construction of the switch and socket is such as to provide for the use of conveniently stamped contact members and switch members adapted to 25 cooperate in the most efficient manner to control the circuit.

The invention comprehends other objects and improvements in the details of construction and arrangement of the parts which are 30 more particularly pointed out in the following detailed description and in the claim directed to a preferred form of the invention, it being understood, however, that various changes in the size, shape and arrangement 35 of the parts may be made without departing from the spirit or scope of the invention as herein set forth.

In the drawings forming part of this application

40 Figure 1 is a vertical sectional view through the socket construction showing the switch construction and insulating plates in elevation with parts thereof broken away in order to clearly illustrate the details of 45 the structure.

Fig. 2 is a view similar to Fig. 1 taken at right angles to Fig. 1.

Fig. 3 is a horizontal sectional view taken on line 3-3 of Fig. 1.

50 Fig. 4 is a horizontal sectional view taken on line 4-4 of Fig. 1.

Fig. 5 is a detail plan view of the switch mechanism and operating member therefor.

55 Fig. 6 is an enlarged detail perspective of the switch member.

Fig. 7 is an enlarged detail perspective of the double contact member.

Fig. 8 is an enlarged detail perspective of one of the single contact members.

Fig. 9 is a diagrammatic view illustrating 60 the wiring connection for the socket and enclosed switch in its associated relation with a wall switch remotely located with respect to the socket, and

Fig. 10 is a detail perspective view of the 65 lower insulating plate.

A pair of insulating plates of annular form are indicated at 1 and 2 respectively which are mounted in spaced parallel relation by a plurality of U-shaped brackets 3 70 which are four in number in the present illustration and mounted in substantially equal spaced relation with respect to each other circumferentially between the plate members. Suitable screw members indicated by the numerals 4 and 5 respectively, secure the plate members to the end portion of these U-shaped bracket members, while the screw members 5 secure the metallic socket electrode 6 to the lower face of the 75 plate member 2, one of the screws 5 having electrical contacts therewith for making circuit connection between one of the brackets and the socket contact 6, while the remaining screws are insulated therefrom by suitable 80 insulating members 7.

The central portion of the upper side of the plate member 2 is formed with a substantially cylindrical upward projection 8 which is cut away to provide a plurality and 85 in the present instance four circumferentially arranged inclined surfaces 9, all of which incline in the same direction. Two of the adjacent inclined surfaces 9 have the contact portions of the single contact members 10 positioned thereon, said contact portions being of arcuate form as indicated by the numeral 11 particularly in Fig. 8. These contact portions 11 of the single contact members extend throughout substantially the 90 entire length of the adjacent inclined portion, terminating slightly short of the end of the said inclined portion. The central outer edges of the contact portions 11 of the single contact members are formed with strip extensions 12 having lateral bent ends 95 which are adapted to seat under the end of the bracket members 3 as illustrated in Figs. 1 and 3 so as to make electrical connection with said bracket member. 100

2
A double contact member is shown at 14 which is provided with a pair of inclined contact portions 15 and 16 respectively which are joined at the offset ends by the portions 17, while the central portion of the contact portion 16 is formed with an outwardly directed angular extension 18' to provide a foot adapted to seat under one of the bracket members 3. The arcuate contact portions 15 and 16 are adapted to seat on the remaining two adjacent inclined portions 9 of the projection 8 for a purpose which will be presently described.

It is noted that the strip portion 18' of the double contact member seats under the bracket 3 which is electrically connected through the screw 5 to the shell electrode 6 so that one portion of the circuit is formed through these members.

20 It should now be understood that the provision of the two single contact members and the double contact member provides electrical connection for circuits to each of these contact members with three of the brackets 3 as illustrated clearly in Fig. 3, while the fourth bracket 3 is adapted to provide electrical connection with the screw 5 securing into the plate member 2 with the central contact 20 within the shell electrode 6 as illustrated in Figs. 1 and 2. This central contact within the shell electrode which receives the central contact on a lamp base is of the resilient strip type adapted to make firm connection with the lamp base when placed in the socket. These bracket members 3 are provided with binding screws 21 to receive the three circuit wire connection from a remotely operated switch, in a manner as will be presently described.

40 The central portion of the insulating plate 2 is formed with a bore 23 while the plate 1 is formed with a socket in axial alignment with the bore 23 for receiving a rod section 24 having the ends seated in the respective aligned bores and secured therein by the assembly of the two plate members through the medium of the brackets 3. A switch member which is formed of stamped sheet material as shown particularly in Fig. 6 and indicated by the numeral 25 is rotatably mounted on the rod 24 which is received through the opening 26. This switch member is formed with switch extensions 27 extending outwardly in opposite directions 55 from the central portion and which are provided with oppositely inclined contact seats 28 arranged in position to seat to the inclined surfaces 9 and the contact members seated thereon in the operation of the switch member.

60 The switch member 25 is provided with angular extensions 29 so as to provide a cruciform central portion around the central opening 26. A disk member 30 is mounted on an insulating plate 31 and is

provided with a plurality of outwardly struck lugs 30' which are adapted to cooperate with the edges of the projections 29 and the switch blades 27 for producing a rotation of the switch in step by step relation 70 in one direction only in the oscillating movement of the plate member 31. The plate member 31 and the disk 30 are provided with openings for rotatable mounting on the rod 24 while the periphery of the plate member 75 31 carries a channel member 32 which is adapted to receive and retain the usual chain pull used in socket constructions of this general character.

80 A spring 33 of coiled form is mounted on the rod 24 between the plate 1 and the plate member 31 for forcing the respective parts including the switch member towards the contact members mounted on the upper face of the plate 2.

85 A suitable form of two part housing having a main body 34 and a cap portion 35 is provided for receiving the above described structure in order to firmly house the same which is lined with an insulating lining 36 in the usual manner, while the cap portion is provided with a cylindrical projection 37 to provide means whereby it may be attached to suitable portions of an electric fixture. The body 34 of the housing is provided at 90 38 with a chain guide for the pull chain adapted to operate the switch mechanism. The spring member 33 furthermore has one end anchored in the plate 1 while the opposite end is anchored as indicated at 39 in the plate member 30 so as to normally rotate said plate member through a quarter turn so that it will be rotated for producing a successive step by step movement in the manual operation thereof in one direction 95 through a quarter turn in the usual manner that pull sockets of this general character are operated in well known two circuit socket constructions.

100 Referring particularly to Fig. 9 showing the wiring diagram of the socket, the shell electrode 6 is connected to the double contact member 14 while the central contact 20 is connected directly with a suitable source of power through the wire 40. The other side of the circuit from the source of contact is provided with a wire connection 41 through a wall switch or other remotely located switch indicated by the numeral 42 which is provided with a movable switch brace 43 and a pair of contacts 44 and 45 respectively. The contacts 44 and 45 are connected by the wires 46 and 47 respectively to the two single contact members 10.

105 It will now be seen that in the operation of the switch member 25 that each pole will rotate the switch member a quarter turn so that it is always maintained in contact at one end or the other with the double contact member while the opposite side is main- 110 115 120 125 130

tained in contact with one of the single contact members. In this way the circuit to the lamp socket can be controlled independently by the switch member 25 to close the circuit to a lamp in said socket or open the same regardless of the position of the switch blades 43. It will also be apparent that the switch blade 43 can be operated to close or open the circuit to the light as desired independently of the switch 25. By the provision of this three way socket and pull switch construction in assembled relation, it will be seen that provision is made for operating a lamp for both the socket and from a remote switch such as a wall switch which may be of any suitable character in order to provide convenient controls for the lamp in the socket.

Having thus described my invention, what I claim as new is:—

A circuit controlling and operating mechanism for three way lamp sockets, compris-

ing a pair of insulating plates, means mounting said plates in spaced parallel relation, circularly arranged ratchet teeth formed on one plate, a pair of single contacts arranged on adjacent ratchet teeth, a double contact mounted on a pair of adjacent ratchet teeth in diametrically opposed relation to the first mentioned pair of ratchet teeth, said double contact being formed of a single strip of substantially semi-circular sheet material having the opposite end portions offset in spaced parallel relation to correspond with the offset of said adjacent ratchet teeth, and a manually operable switch having the central portion rotatably mounted between the plates and the ends adapted to engage one of the single contacts and one offset portion of said double contact in each position of rotation.

In testimony whereof I affix my signature.

CLARENCE SCHULDT.
